DESIGN FOR A HANDKERCHIEF OR SIMILAR ARTICLE

Winifred S. Mogabgab, New York, N. Y.

Application January 13, 1945, Serial No. 117,403

Term of patent 14 years

(Cl. D3—12)

To all whom it may concern:

Be it known that I, Winifred S. Mogabgab, a citizen of the United States of America and a resident of the city, county, and State of New York, have invented a new, original, and ornamental Design for Handkerchiefs or Similar Articles, of which the following is a specification, reference being had to the accompanying drawing, forming a part thereof.

In the drawing:

Fig. 1 is a plan view of a handkerchief broken away along the dash and dot lines to show the four corners and disclosing my new design and

Fig. 2 is a view in side elevation looking upwardly at the lower edge of Fig. 1.

I claim:

The ornamental design for a handkerchief or similar article, as shown.

WINIFRED S. MOGABGAB.
